EXTENSION LADDER

Wilhelm Adolf Hummel, Ulm-on-the-Donau,
Germany, assignor to firm C. D. Magirus Ak-
tiengesellschaft, Ulm-on-the-Donau, Germany

Application July 20, 1931, Serial No. 552,016
In Germany July 23, 1930

9 Claims. (Cl. 228—18)

My invention relates to extension ladders having telescoping units.

It is an object of my invention to provide an improved ladder of the type aforesaid. To this end I make its units of closed hollow metal sections.

Such sections are employed for the principal parts of the ladder, such as its side pieces, rungs, etc.

10 I may make the sections with any number of braces therein, or combine several sections in such manner that they brace each other.

Sections according to my invention have the advantage that they are not only strong against compression, tension and bending at right angles to the plane of the units but also against bending moments in the plane of the units and against torsion.

15 It is another object of my invention to eliminate unsymmetrical tensions in the sections of the side pieces to which end the side piece sections are made symmetrical to their central vertical plane.

It is still another object of my invention to 20 provide a particularly simple design of the side pieces. To this end I built up the side pieces from an upper and a lower flanged section, of U or V shape, and a horizontal brace between the flanges which is preferably welded thereto. The 25 flanges serve also for guiding the several telescoping units of the ladder with respect to each other.

Any other sections may be used for building up 30 side pieces and other parts of the units. A particularly favorable section with regard to strength and stiffness of its side pieces is one that has the shape of a T, with one or more bracings in its central plane at right angles to the plane of the unit.

40 A section which is particularly favorable with respect to the guiding of the units is obtained by combining sections resembling the letters S or Z, with box girders as the bars of the S or Z sections, and the horizontal girders equipped with rollers 45 for guiding the units.

The rungs of the units may also be made of sections which may be open or closed and are readily connected to the sides or the flanges of the side-piece sections so as to be stiff against bending and torsion, for instance, by welding.

50 It is still another object of my invention to provide improved means for bracing the side pieces. To this end I design the bracing means like lattice work built up from closed hollow sections, and

arrange them preferably symmetrically to the central vertical plane of the side-piece sections.

It is still another object of my invention to provide improved means for guiding the telescoping units with respect to each other, as will be 5 described.

In the accompanying drawings various ladders embodying my invention are illustrated diagrammatically by way of example.

In the drawings

Fig. 1 is an elevation of a truck having an extension ladder of four units.

Fig. 2 is a rear end elevation of the truck,

Fig. 3 is a section at right angles to the side pieces of a ladder showing side pieces built up 15 from flanged V sections,

Figs. 4 and 5 are sections on the lines IV—IV and V—V in Fig. 3,

Fig. 6 is an elevation showing part of the lattice work for bracing the side pieces,

Fig. 7 is a section on the line VII—VII in Fig. 6,

Fig. 8 is a cross section of three units having side pieces built up from two channel sections each to form a double T, or I,

Fig. 9 is a section on the line IX—IX in Fig. 8 in which the upper part of the ladder is not shown in order to save space,

Figs. 10, 10a, and 10b show sections of modified double-T side pieces,

Fig. 11 is a cross section of three units having side pieces built up from trapezium sections,

Fig. 12 shows a modified trapezium section,

Figs. 13 and 14 show two types of rectangular sections,

Fig. 15 is a section on the line XV—XV in Fig. 11 in which the upper part of the ladder is not shown in order to save space,

Fig. 16 is a cross section of three units having Z shaped side pieces from three box girders,

Fig. 17 is a section on the line XVII—XVII in Fig. 16 in which the upper part of the ladder is not shown in order to save space,

Figs. 18 and 19 show modified Z sections,

Fig. 20 is an elevation showing part of two 45 units, with rocking guide rollers,

Fig. 21 is a section on the line XXI—XXI in Fig. 20,

Fig. 22 is an elevation showing two of the rocking rollers, with their supporting arm,

Fig. 23 is a section on the line XXIII—XXIII in Fig. 22, and

Fig. 24 shows two more rocking rollers.

Referring now to the drawings, and first to Figs. 1 and 2, A is the ladder in collapsed condi-

10

tion, and B is the truck on which it is carried. C, D, E, F are its four telescoping units, each with a pair of side pieces, and pillars 16, diagonals 20, and a hand rail 19 per side piece.

Referring now to Figs. 3 to 7, 1 are the side pieces at one side of the four telescoping units. The lowest side piece comprises a flanged V section 2 which may be rolled or pressed, and a stay 5 secured to the flanges 3, 4 of the inverted V section 2. 12 is a bearing sleeve, which is secured in the section 2 by welding or in any other suitable manner, 11 is a pin in the sleeve, 10 is a roller on the pin, and 13 is a bearing for the free end of the pin which is welded, or otherwise secured to, the bottom plate of a rung 14, as best seen in Fig. 5. The top of the rung is supported by a tubular transverse stay 33. The side pieces of the units above the lowest unit are equipped with channel sections 7 below the stays 5 of their sections 2, with their flanges 8 and 9 welded or otherwise secured to the stay 5. The channel sections 7 are races for the rollers 10. Obviously I am not limited to channel sections, but may provide V or flat tubular sections etc. instead. The units are held in position in upward direction by checks 17 at the apices of the V sections 2, and by rollers 15 on pins 83 in the pillars 16. The checks 17 are angular and lined with wear plates 18 opposite depending portions at the inner sides of the stays 5, or the flanges 3 or 8. The checks 17 have inwardly projecting flanges 17'.

The sections from which the side pieces are built up may be made in any suitable manner, for instance, by being rolled or by being drawn from separate bars or as a single bar.

The hand rail 19, Fig. 6, the pillars 16 and the diagonals 20 are also made of hollow sections like the side pieces 1, in order to increase their compression strength.

40 The rungs 14 in this figure are shown only by way of example. Other possible forms for these rungs are indicated in the other figures of the drawings.

The units shown in the other figures, with their side pieces 1, their pillars 35, 52, 75, and 92, their diagonals 20 and 76, and their hand rails 36, 51, and 71, are designed as described with reference to Figs. 1 to 7.

Referring now to Figs. 8 and 9, the side pieces 1 are double T or I section 21, consisting of two hollow channel sections 22, 23, and a stay 24 placed centrally between them. The stay is preferably welded to the sections 22, 23.

The side pieces are held against displacement in vertical direction by the interlocking of the flanges 28, 29 of the T's, and supported on rollers 30 which are seated on the pins 11. The pins are held in sleeves 31 of the sections, at one end, and by bearings 34 on the rungs 32 at the other. The ends of the rungs are welded to the inner flanges of the sections 22, or otherwise secured thereon.

Referring to Fig. 10, the T's 21 may also be built up from two hollow channels 25, 26 which are connected at their webs 27, for instance by welding.

Referring to Figs. 10a and 10b, two hollow sections 25a and 26a may be placed end to end with their webs, and connected by welding or the like. A vertical stay may be dispensed with here or be replaced by a horizontal stay. If a vertical stay 24a is provided it is equipped with tabs 24b at its upper and lower edges which are inserted in suitable holes in the flanges.

Referring to Figs. 11 and 15, the side pieces 1 are double-trapeze sections, being built up from

two channel sections 38 and 39 to make up a hollow section 37 with two central ridges, the rollers 53 on their pins 11 in sleeves 56 and bearings 58 on the base 57 of rungs 50, here shown as square tubes, being notched in conformity with the ridges. Rails 55 are secured to the outer sections 39 and rollers 54 on pins 88 in the pillars 52 bear on them.

The side pieces may be braced by a vertical stay 42, or they may be built up from two tubes 44, 10 45, with their longer webs 48 connected by welding or the like. Trapeze sections may be replaced by rectangular channel sections, 40, 41, Fig. 13, with a vertical stay 43 between them. As shown in Fig. 14, two tubes of rectangular section 46, 15 47 may be connected by their webs 49.

Referring to Figs. 16 and 17, the side pieces are here built up from three rectangular tubes arranged in the shape of the letter Z. Fig. 19 shows the side piece disassembled. It consists of two bars 59 and 60 each bent to a rectangle at one end, and to a hook at the other. The flanges of the bars forming the rectangles are welded to their webs at 63 and 64, respectively, and to each other's webs at 66, 62. The webs 63 and 66 form 23 the stays for the sections. 73 are tubular braces connecting the side pieces 1, and 12 are rollers on the braces which support the side pieces 1. The lower flange of each side piece engages below the upper flange of the adjacent side piece, 30 as shown at 70 and 71. Antifriction liners may be inserted at these points.

74 are the rungs.

Referring to Fig. 18, the side pieces are built up from three independent square tubes 67, 68, 35 69 which may be connected by welding.

The units interengage for a certain distance when the ladder is extended. Seizing at these points must be avoided so that the units are readily displaced. To this end I provide rocking 40 supports for the rollers at the inner ends of the units, and also for the rollers which engage the units from above, as shown in Figs. 20 to 24.

The sections of the side pieces 78, 86, Fig. 21, are the same as shown in Fig. 3. 79 is a pin secured partly in the section 78 and partly in a bearing 81 on the base of a rung 82. 80 is a rocking arm, and 84, 84 are supporting rollers mounted to rotate about pins 83 at the ends of the arm. The rail 85, Fig. 21, of the lower section at each side piece runs on the rollers 84, 84. Any number of rollers may be arranged on a rocking arm.

The rollers 80 which bear on the flanges 81 of the side pieces, Fig. 21, are also arranged at opposite ends of an arm 87 and mounted to rotate about pins 89 at the ends of the arm which in turn is mounted to rock about a pin 93 in a pillar 92, or at any other suitable point. Any number of rollers may be arranged on the arms 87.

It will be understood from the foregoing description that my invention may be modified in various ways without departing from its gist, and in particular I wish to emphasize that I am not limited to any particular section, or combination 65 of sections, nor to any particular method or means for connecting the sections to each other or to other members. Welding is generally preferred but the parts may also be riveted or secured in any other suitable manner. The sections may 70 be obtained in any suitable way and may be commercial or special sections, as required.

Although a ladder consisting of three parts is shown in the drawings, the invention is not restricted to this particular form but covers any 75

constructional embodiment of a ladder comprising a plurality of parts.

I claim:

- 5 1. An extension ladder comprising telescoping units, metal side pieces of closed hollow cross section built up of section elements on said units, bracing means in said side pieces, bearings spaced from said side pieces and secured to rungs, pins extending through said side pieces and bearings, 10 and supporting rollers for the side piece arranged above said pins.
- 15 2. An extension ladder comprising telescoping units, metal side pieces of closed hollow cross section built up of section elements on said units, 15 bracing means in said side pieces, supporting rollers on said side pieces on which the side piece of the next unit is carried, and rollers on rocking supports bearing on said side pieces from above.
- 20 3. An extension ladder comprising telescoping units, metal side pieces of closed hollow cross section on said units, rungs connecting said side pieces, bearing pins supported in said side pieces at one end, and on said rungs at the other end, 20 rocking arms on said pins, and rollers on said arms for supporting the side piece of the unit above.
- 25 4. An extension ladder comprising telescoping units, said units having two longitudinal elements secured together by rungs and each formed of a longitudinal bracing element and two longitudinal members cup-shaped in cross section, the edges of said members being secured to said bracing element, bearings mounted on said rungs and spaced from said longitudinal elements, pins 30 extending through said longitudinal members and bearings, and supporting rollers mounted on said pins for the longitudinal elements of the adjacent telescopic section of the extension ladder.
- 35 5. An extension ladder comprising telescoping units, said units having longitudinal side elements of sheet metal connected by rungs, each of said longitudinal side members being comprised of a longitudinal transverse bracing element, an upper longitudinal member substantially 35 in the form of an inverted U in cross section and a lower longitudinal member substantially U-shaped in cross-section, the end portions of said U-shaped members having outwardly 40 extending flanges secured to said longitudinal bracing element, said upper inverted U-shaped member being provided at its apex with an inwardly extending portion adapted to form a guide for the flange on the inverted U-shaped member of the adjacent telescopic section of the extension ladder, and rollers 45 on the side pieces of each telescopic section and adapted to abut the U-shaped section of the side members of the adjacent telescopic section of the ladder.
- 45 6. An extension ladder comprising telescoping units, said units having longitudinal side elements 5 of sheet metal connected by rungs, each of said longitudinal side members being comprised of a longitudinal transverse bracing element, an upper longitudinal member substantially 10 in the form of an inverted U in cross-section and a lower longitudinal member substantially U-shaped in cross section, the end portions of said U-shaped members having outwardly extending flanges secured to said longitudinal bracing element, said upper inverted U-shaped member being provided at its apex with an inwardly extending portion 15 adapted to form a guide for the flange on the inverted U-shaped member of the adjacent telescopic section of the extension ladder, and rollers 20 on the side pieces of each telescopic section and adapted to abut the U-shaped section of the side members of the adjacent telescopic section of the ladder.
- 50 7. An extension ladder comprising telescopic units, side pieces of closed hollow metal sections on said units, each of said side pieces being provided with a portion which extends substantially at the top beyond the plane of the side thereof to form a guide for the adjacent telescopic section 30 of the ladder, said extending portions overlapping a portion which extends from the adjacent section at a point intermediate the top and bottom of said adjacent section.
- 55 8. An extension ladder comprising telescopic units, side pieces of closed hollow metal sections on said units, each of said side pieces being provided with a portion which extends substantially at the top beyond the plane of the side thereof to form a guide for the adjacent telescopic section 40 of the ladder, said extended portion being formed from longitudinal sheet metal portions which in their turn form parts of the closed hollow metal sections and are connected with the other longitudinal elements forming said sections 45 by welding.
- 60 9. An extension ladder according to claim 8, longitudinal bracing members inserted between the longitudinal member provided with the extended portion and the other longitudinal member completing said hollow metal sections and secured together by welding.

WILHELM ADOLF HUMMEL.
